UNITED STATES PATENT OFFICE.

ANDREW H. PALMBUSH, OF CONRAD, MONTANA.

SHOCK-FORMING DEVICE.

1,389,779.

Specification of Letters Patent.

Patented Sept. 6, 1921.

Application filed April 9, 1918, Serial No. 227,546. Renewed December 31, 1920. Serial No. 434,382.

To all whom it may concern:

Be it known that I, ANDREW H. PALMBUSH, a citizen of the United States, residing at Conrad, in the county of Teton and 5 State of Montana, have invented certain new and useful Improvements in a Shock-Forming Device, of which the following is a specification.

This invention relates to improvements in 10 harvesting apparatus and it is the principal object of the invention to provide a device for receiving sheaves from a binding mechanism and arranging the same, then deposit them on the field or other surface in shock 15 form, thus, obviating the necessity of gathering the sheaves discharged from the binding mechanism and shocking the same manually; hence, effecting a material saving in time and labor.

20 Another and equally important object of the invention is to provide the device with a novel form of basket or former for receiving the sheaves and arranging the same to constitute the usual shock on the field over 25 which the device is moving when a predetermined number of sheaves have been deposited therein from the binding mechanism.

Other independent objects are to provide 30 features of construction of portions of the device which tend toward the attainment of the aims irrespective of the relation in which they are used.

The invention accordingly consists in the 35 features of construction, combinations of elements and arrangement of parts which will be exemplified in the construction herein-after set forth and the scope of the application of which will be indicated in the following claims.

In the accompanying drawings, wherein is shown one of various possible embodiments of my invention:

Figure 1 is a top plan of the improved 45 device having parts thereof broken away and shown in section,

Fig. 2 is a side elevation thereof,

Fig. 3 is a vertical transverse section through the same,

50 Fig. 4 is a fragmentary detail partly in section of the novel form of clutch employed, and

Fig. 5 is a fragmentary detail in perspec-

tive showing the mounting of the former carrying shaft.

Having more particular reference to the drawings, in connection with which like reference characters will designate corresponding parts throughout the several views, 1 represents the frame of the device, the same 5 being substantially triangular in shape and mounted upon suitable wheels, not shown. An endless conveying belt 2 is mounted on the usual pulleys journaled in bearings in the opposite ends of the inclined portion of 10 the frame 1 and as will be understood, is arranged to communicate with the sheaf receiving and discharging basket arranged on a binding mechanism to which my improved device is attached.

70 In order that motion may be transmitted to the endless belt conveyer 2, the shaft carrying the lower pulley has one end thereof extended as indicated by the numeral 3 and has interengageable clutch elements 4 and 5 75 loosely mounted thereon, the slideable clutch element 4 being formed with the usual serrated portions upon each of the ends, one of which is adapted to engage with a pin 6 passing through the extended end 3 of the 80 shaft, while the remaining portion is adapted to be engaged with the adjacent face of the non-slideable clutch elements 5. A sprocket wheel 7 is mounted on the clutch 4 and receives the usual form of sprocket 85 chain, not shown, thereabout, which chain has connection with drive means arranged on the binding mechanism to which the device is connected. The remaining clutch 5 is provided with a form of windlass 8 having one end of a cable 9 secured thereto as 90 at 10, the remaining end of the cable extending forwardly into engagement with a lever, hereinafter more fully described. To normally maintain the clutches 4 and 5 disengaged, an expandable coil spring 11 is interposed therebetween; the opposite convolutions thereof being arranged against the adjacent portions of the clutches. Slidably mounted on the extremity of the extension 95 3 is an operating arm 12, which as will be noted, has bearing on a casing sleeve 13 arranged over the clutch element 4. One end of the arm 12 is connected to a link 14 having connection with a portion of the frame 1, 100 while the remaining end thereof is connect-

ed to an operating cable 15 passing over a suitable pulley 16 arranged on said frame 1 into engagement with operating means mounted on the binding mechanism at a 5 point convenient to the operator. Obviously when a motion transmitting chain from the binder is operating about the sprocket wheels 7 the conveyer will be in operation but by pulling the cable 15, the 10 arm 12 will be moved inwardly and as a consequence, the clutch 4 will be disengaged from the pin 6 so as to be loose on the shaft extension and engaged with the clutch 5, thus imparting rotary motion to the same 15 and to its windlass 10, and coiling the cable 9 thereabout without actuating the conveyer.

Arranged transversely of the lower portion of the frame 1 is a shaft 17 having arms 20 18 secured thereto in spaced relation, which arms are pivotally connected to other arms 19 having pivotal connection with the former carrying frame 20. As will be noted, the frame 20 is substantially square and has 25 the rear end thereof pivotally engaged with hangers 21 pivotally connected to the inclined sides of the frame 1, while the forward portion thereof is pivotally connected to other hangers 22 which, as will be noted, have pivotal connection with the vertically 30 disposed sides of the frame 1.

Disposed longitudinally of the frame 20 and rotatably mounted in bearings 23 and 23' arranged thereon is a shaft 24, the forward portion of which is flattened and curved slightly in order that the same can be connected to the shock forming element 25 by bolts 26 or similar fastening devices which are passed therethrough into engagement with said flattened end. In this connection, it is to be noted that the former 25 is secured to the flattened end of the shaft 24 at a point off-center and as a consequence, when the former is filled with sheaves, the 35 same will be overbalanced and caused to rotate in a direction such as will effect the discharge of the sheaves therefrom onto the field or other surface over which the device is moving. To limit rotary motion of the 40 shaft 24, certain of the ends of the bearings 22 and 23 are notched as at 27 and receive therein cross pins 28 passing through the adjacent portions of the shaft 24.

Fixedly mounted on the intermediate portion of the shaft 24 is a drum 29 having a contractile coil spring 30 arranged thereabout, one end of which is secured to the periphery thereof as at 31 while the remaining end is connected to a cable or like connection 32 secured to a portion of the former carrying frame 20 as at 33. Hence, when the former 25 is rotated due to the overbalancing of the same, the shaft 24 will serve to place the contractile spring 30 under tension. As 35 a consequence, when the sheaves have been

discharged from the former in shock form the same will be immediately returned to its normal position due to the connection of said spring 30 with the drum 29.

The former 25 comprises a substantially 70 cylindrical element having the sides thereof tapered and the upper portion of the same open and formed with upwardly extending flared guides 34, which guides, obviously, serve as means for directing the sheaves delivered from the binding mechanism into the former. Due to the tapering of the former, the sheaves will be properly arranged and when discharged onto the field will constitute the usual shock. 75

To prevent the sheaves delivered into the former from falling therefrom, a gate 35 is provided and is carried upon a substantially horizontally disposed arm 36 arranged on the upper end of a vertically disposed shaft 85 37, which as will be noted, is journaled in bearings 38 arranged on one side of the frame 1 and carries an arm 39 upon its lower end, which arm is pivotally engaged by a link 40 having pivotal connection with another arm 41 fixedly mounted on the transversely disposed shaft 17. Hence, when the shaft 17 is rotated, rotary motion will be imparted to the shaft 37 thereby causing horizontal movement of the arm 36 and 90 thereby moving the gate 35 out of engagement with the adjacent open end of the former 25. To prevent rotation of the former 25 while in a position adjacent the gate 35, a segmental arm 42 is arranged on one end thereof and is adapted to be engaged with the upper portion thereof. In this way, it will be understood that the former will be prevented from rotating until the segmental arm 42 is disengaged from the 95 gate 35.

The operation of my improved device may be reviewed as follows:

The device is attached to the usual form of binding mechanism at a point adjacent the sheaf receiving and discharging basket thereof. Power is transmitted to the endless belt 2 by way of the sprocket wheel 7 and the chain arranged thereabout and as a consequence, the sheaves discharged from 110 the sheaf receiving and discharging basket of the binding mechanism will be delivered onto said conveyer and carried upwardly thereby whereupon they will be discharged into the former 25 and properly arranged 115 to constitute the usual shock. When a sufficient number of sheaves have been discharged into the former, the cable 15 is pulled to effect disengagement of the clutch 4 from the shaft extension 3 and to engage 120 the same with the clutch 5, whereupon the cable 9 will be coiled thereabout and as a consequence, the arm 17' will be rocked to cause the frame 20 to move forwardly, then 125 upwardly. At the same time, the shaft 37 130

will be rotated thereby causing the arm 36 and the gate 35 carried thereby to be moved out of engagement with the adjacent open end of the former 25 and also out of engagement with the segmental arm 42 secured thereto. Due to the fact that the former 25 is mounted off-center on the shaft 24, the same will be overbalanced and will rotate to a position whereupon the sheaves will be discharged therefrom onto the field in form of a shock. As hereinbefore stated, rotary movement of the shaft 24 and as a consequence, the former 25 is limited by reason of the engagement of the pins 28 with the notches 27 formed in the adjacent ends of the several bearings 22 and 23. When the sheaves have been discharged from the former, the spring 30 will then serve to return the same to its normal position ready for further operation. Furthermore, after the former 25 has been rotated to its discharging position, the cable 15 is released, thereby causing the clutches 4 and 5 to be disengaged and reestablishing connection between the clutch 4 and the extended end 3 of the shaft carrying the lower pulley of the conveying means. By reason of the disengagement of the clutch 4 from the shaft extension 3, it will be also understood that travel of the endless conveyer belt will be temporarily discontinued and therefore, sheaves will not be discharged from the same onto the former until the same has returned to its normal position with respect thereto.

Manifestly, the construction shown is capable of considerable modification and such modification as is within the scope of my claims, I consider within the spirit of my invention.

I claim:

1. In a device of the character described, a main frame, conveying means on said frame, coacting clutch means associated with the conveying means and arranged so that the conveying means normally operate, a secondary frame movably supported in the main frame, means for operably connecting the secondary frame with the clutch means, shock forming means rockably mounted in the secondary frame, retaining means engaged with one end of the shock forming means for preventing rotation thereof, and other means connected to the secondary frame and operable when the secondary frame is moved for effecting disengagement of the forming means from the retaining means.

2. In a device of the character described, a main frame, conveying means on said frame, a secondary frame movably suspended in the main frame beneath the conveying means, a rock shaft in the main frame, a longitudinally disposed shaft rockably mounted in the secondary frame, shock forming means carried by the outer end of

the longitudinally disposed rock shaft, an operable connection between the rock shaft and the main frame and the secondary frame, retaining means mounted on the main frame for preventing accidental rotation of the shock forming means and operably connected with the rock shaft in the main frame, means for actuating the rock shaft in the frame to release the shock forming means, and spring means engaged with the longitudinally disposed rock shaft for returning the shock forming means to normal position subsequent to actuation thereof.

3. In a device of the character described, a main frame, conveying means on said main frame, a secondary frame movably supported on the main frame, a shaft on the secondary frame, shock forming means carried by said shaft, a rock shaft in the main frame, an operable connection between the rock shaft and the secondary frame, retaining means associated with the shock forming means and operably connected with the rock shaft, a shaft extension projecting from the conveying means, normally disengaged clutch members on the shaft extension one of which is loose thereon while the other is releasably fixed thereto so as to normally cause the actuation of the conveying means, an operable connection between the rock shaft and the loose clutch member, and manually operable actuating means for sliding the releasably fixed clutch member into engagement with the loose clutch member to cause the rocking of the shaft in the main frame and the subsequent operation of the shock forming means, and spring means engaged with the shaft in the secondary frame for returning the shock forming means to normal position subsequent to actuation thereof.

4. In a device of the character described, a main frame, conveying means on said frame, a shaft extension in connection with the conveying means, clutch members on the shaft extension one of which is loose and non-slidable while the other is slidable, spring means for normally holding the members disengaged, coöperative means on the shaft extension and slidable clutch member for connecting said member with the shaft, a sprocket wheel carried with the slidable clutch member and with which motion transmitting means is adapted to be associated, a drum carried with the loose clutch member, a secondary frame movably supported in the main frame and arranged beneath the conveying means, a rock shaft in the main frame, an operable connection between the shaft and the secondary frame, a cable having one end operably connected with the rock shaft and the other end connected to the drum, shock forming means rockably mounted in the secondary frame, retaining means engaged with one end of

the forming means for preventing rotation thereof and operably connected to the rock shaft, and manually operable actuating means on the shaft extension for sliding the 5 slideable clutch member into engagement with the other clutch member whereby to temporarily stop the operation of the conveying means and effect an operation of the shock

forming means, and spring means for automatically returning the shock forming 10 means to normal position subsequent to the actuation thereof.

In testimony whereof, I affix my signature hereto.

ANDREW H. PALMBUSH.
